HAND STRAP

Everard C. Mersereau, Staten Island, N. Y., assignor to The Elcon Company, a corporation of New York

Application July 26, 1947, Serial No. 763,977

8 Claims. (Cl. 105—354)

1

This invention relates to hand straps of the kind commonly provided in subway, elevated, and surface passenger cars for the use of standing passengers. More particularly, the invention is concerned with a novel hand strap, which is an improvement in both appearance and construction over prior similar hand straps.

At the present time, one form of hand strap in use includes an attaching bracket secured to a part of the car, a hanger pivotally attached to and depending from the bracket, and a hand loop attached to the free end of the hanger. The hand loop is made from a length of tubing, and the free end of the hanger has the form of a flat strip. The ends of the loop are flattened, placed against opposite faces of the flat strip end of the hanger, and secured thereto by a plurality of rivets. With this construction, the smooth lines of the hanger and loop are broken by the portions of these parts, that are connected together, and by the heads of the rivets, that are visible at opposite faces of the connection. Also, a number of operations are required to prepare the parts to be connected together and to make the actual connection.

The new hand strap includes a hanger pivotally attached to the bracket and having a hollow free end. The hanger is of increasing width toward its free end and preferably has flat parallel faces joined by outwardly divergent curved end walls. The hand loop is preferably made from a length of tube, the ends of which converge and enter the open end of the hanger. The loop is held in place by having its ends clamped against the inner surfaces of the end walls of the hanger and, for this purpose, a wedge block is placed between the ends of the loop and forced into the hanger by suitable means. The wedge block and the ends of the loop have interengaging parts and the block lies within the end of the hanger and closes the space between the ends of the loop. As a result, the loop is held securely in place and the means for attaching the loop are largely concealed and do not detract from the appearance of the hand strap.

For a better understanding of the invention, reference may be had to the accompanying drawing, in which:

Fig. 1 is a view in side elevation, with parts broken away, of a hand strap embodying the invention;

Fig. 2 is a sectional view on the line 2—2 of Fig. 1, but on a larger scale;

Fig. 3 is an end view of a wedge block employed in the new hand strap; and

2

Fig. 4 is a sectional view on the line 4—4 of Fig. 3.

The hand strap in the form shown in Fig. 1 includes an attaching bracket 10, of which a part only is shown, and the bracket is secured to a suitable part of the car and ordinarily projects downwardly at an angle therefrom, as indicated. A hanger 11 is connected to the bracket to swing about a pivot pin 12, and the bracket and the pivotal connection of the hanger thereto are preferably of the construction shown in Munro and Dilg Patent 2,137,622, issued November 22, 1938.

The hanger has a hollow lower end and is preferably formed with opposed flat faces 13, 14 connected by curved end walls 15, 16, which diverge toward the free end of the hanger. The hand strap includes a hand loop 17, which may advantageously be formed of a length of tubing bent to appropriate shape. The ends of the loop enter the open end of the hanger and are secured in place by clamping means including a wedge block 18, which has concave outer walls 19, 20 conforming generally to the curvature of the tubing 17. The wedge block has a recess 21 in its larger end and a passage 22 leads through the block from the bottom of the recess. A bolt 23 extends through the block and is threaded into a projection 24 from the inner wall of the hanger. The head of the bolt engages the bottom of recess 21 around the passage 22. A stop 25 is formed on the inner wall of the hanger adjacent projection 24 and one end of the loop 17 abuts the stop. The block has transverse lugs 26 across its outer walls and the opposed faces of the ends of the loop have openings 27, in which the lugs are received.

The connection of the loop and hanger is effected, as follows: The wedge block is placed between the ends of the loop with its lugs 26 in the openings 27 and the loop ends and block are inserted in the open end of the hanger. Bolt 23 is passed through the block and threaded into projection 24. When the bolt is tightened, the block moves into the hanger, drawing the loop ends with it, until one end of the loop engages stop 25. Further tightening of the bolt causes the block to move relatively to the loop ends to force the ends into tight clamping engagement with the walls of the hanger, the lugs 26 having sufficient play in openings 27 to permit such movement of the block relative to the loop. The parts are so proportioned that, when the block 18 is in tight clamping engagement with the ends of the loop, the outer surface of the block lies flush

with or within the free end of the hanger. The space between the ends of the loop is thus closed by the block and the block is not visible from the side of the hand strap. The bolt 23 is wholly concealed, since the recess 21 is longer than the height of the bolt head.

The new hand strap is more attractive in appearance than those heretofore made, in that the hanger and loop have smooth lines and there is no flattening of the ends of the loop. Also, the means for connecting the loop and hanger are concealed and the hand strap includes no rivets with exposed heads. The hanger and loop may be formed in a few operations and the connection of the loop to the hanger is simple and effective.

I claim:

1. In a hand strap, the combination of a hanger having means at one end for reception of a pivot, the other end of the hanger being open and having opposed inwardly convergent walls, a hand loop of rigid tubular material having its end portion entering the open end of the hanger between said walls, a wedge block between the end portions of the loop, the block and the end portions of the loop having interengaging parts, and means engaging the hanger and block and operable to apply pressure through the block to clamp the end portions of the loop between the block and said walls and to hold said parts in engagement.

2. In a hand strap, the combination of a hanger having means at one end for reception of a pivot, the other end of the hanger being open and having opposed inwardly convergent walls, a hand loop of rigid tubular material having its end portions entering the open end of the hanger between said walls, a wedge block between the end portions of the loop, the block and the end portions of the loop having interengaging parts, and a bolt passing through the block and into a portion of the hanger, the head of the bolt engaging the block and the bolt being operable to cause the block to clamp the end portions of the loop between the block and said walls and to hold said parts in engagement.

3. In a hand strap, the combination of a hanger having means at one end for reception of a pivot, the other end of the hanger being open and having opposed inwardly convergent walls, a hand loop of rigid tubular material having its end portions entering the open end of the hanger between said walls, a wedge block between the end portions of the loop, the block and the end portions of the loop having interengaging parts, a stop within the hanger for limiting inward movement of the loop end portions, and means engaging the hanger and block and operable to apply pressure through the block to clamp the end portions of the loop between the block and said walls and to hold said parts in engagement.

4. In a hand strap, the combination of a hanger having means at one end for reception of a pivot, the other end of the hanger being open and having opposed inwardly convergent concave walls, a hand loop of rigid tubular material of circular cross-section having its end portions entering the open end of the hanger between said walls, a wedge block between the end portions of the loop, the block having concave walls engaging the surfaces of the end portions of the loop and the block and the end portions of the loop having interengaging parts, and means engaging the hanger and block and operable to move the block into the hanger and thereby clamp the end portions of the loop between the

block and said walls and to hold said parts in engagement.

5. In a hand strap, the combination of a hanger having means at one end for reception of a pivot, the other end of the hanger being open and having opposed inwardly convergent walls, a hand loop of rigid tubular material having its end portions entering the open end of the hanger between said walls, a wedge block between the end portions of the loop, the block and the end portions of the loop having interengaging parts, an inward projection from one wall of the hanger at a point spaced from the open end, a stop within the hanger for engagement by one end of the loop, and a bolt passing through the block and threaded into the projection, the head of the bolt engaging the block and the block clamping the end portions of the loop between the block and said walls.

20 6. In a hand strap, the combination of a hanger having means at one end for reception of a pivot, the other end of the hanger being open and having opposed inwardly convergent walls, a hand loop of rigid tubular material having its end portions entering the open end of the hanger between said walls, a wedge block between the end portions of the loop, and means engaging the hanger and block and operable to apply pressure through the block to clamp the end portions of the loop between the block and said walls, the opposite walls of the wedge block engaging the inside of the end portions of the loop for substantially their entire length and having a concavity conforming to the contour of the end portions of the loop with which they engage, whereby a surface contact between said block and the end portions of the loop is provided, the outside of the end portions of the loop having a convergency conforming to that of the convergent walls of the hanger so that an extended contact between the end portions of the loop and said convergent walls of the hanger is obtained.

30 7. In a hand strap, the combination of a hanger having means at one end for reception of a pivot, the other end of the hanger being open and having opposed inwardly convergent walls, a hand loop of rigid tubular material having its end portions entering the open end of the hanger between said walls, a wedge block between the end portions of the loop, a stop within the hanger for limiting inward movement of the loop ends, and means engaging the hanger and block and operable to apply pressure through the block to clamp the end portions of the loop between the block and said walls, the opposite walls of the wedge block engaging the inside of the end portions of the loop for substantially their entire length and having a concavity conforming to the contour of the end portions of the loop with which they engage, whereby a surface contact between said block and the end portions of the loop is provided, the outside of the end portions of the loop having a convergency conforming to that of the convergent walls of the hanger so that an extended contact between the end portions of the loop and said convergent walls of the hanger is obtained.

40 8. In a hand strap, the combination of a hanger having means at one end for reception of a pivot, the other end of the hanger being open and having opposed inwardly convergent walls, a hand loop of rigid tubular material having its end portions entering the open end of the hanger between said walls, a wedge block between the end portions of the loop, an inward projection

from one wall of the hanger at a point spaced from the open end, a stop within the hanger for engagement by one end of the loop, and a bolt passing through the block and threaded into the projection, the head of the bolt engaging the block and the block clamping the end portions of the loop between the block and said walls, the opposite walls of the wedge block engaging the inside of the end portions of the loop for substantially their entire length and having a concavity conforming to the contour of the end portions of the loop with which they engage, whereby a surface contact between said block and the end portions of the loop is provided, the outside of the end portions of the loop having a convergency conforming to that of the convergent walls of the hanger so that an extended

contact between the end portions of the loop and said convergent walls of the hanger is obtained.
